RECEIVING ARRANGEMENT FOR
RADIOSIGNALS

Fritz Schröter and Wilhelm Runge, Berlin, Germany, assignors to Telefunken Gesellschaft für Drahtlose Telegraphie m. b. H., Berlin, Germany, a corporation of Germany

Application January 30, 1929, Serial No. 336,038,
and in Germany February 13, 1928

6 Claims. (Cl. 250—2)

The present invention relates to the reception of signals transmitted through space on short electromagnetic waves.

The invention, more particularly speaking, concerns an arrangement whereby the disturbances to the service caused by fading are diminished. This end is attained by diversity reception, that is, by the provision of several antenna systems or antenna systems having different fading characteristics, preferably by being mounted at comparatively great distance from one another, and of a special receiver circuit upon which the different antenna systems are brought to act. The said receiver circuit, according to our invention, consists of an A. C. circuit which is influenced by the impulses fed therein from the respective antenna systems, in such a way that an indicator or translating device which is connected with the A. C. circuit is rendered operative even when impulses are coming in from one of the antenna systems only, and the result is that the indicator outfit will record the signals when several of the other antenna systems fail to pick up signals owing to fading.

25 The single figure of the drawing illustrates the preferred embodiment of the invention.

Referring to the drawing, A1, A2, A3, are three antennas or antenna systems mounted apart from one another at distances which are not small compared with the working wave. The oscillations picked up by each one of these antennas are fed, preferably after amplification, to the respective rectifiers g1, g2, g3, the amplifiers being denoted by v1, v2, v3. Now, these 35 rectified currents serve to act upon three thermionic tubes connected with an A. C. circuit fed from an A. C. generator H in such a manner that the intensity of the A. C. supplied from said generator H is caused to vary at the rhythm of the 40 incoming signals in said A. C. circuit, with the result that an indicator or recorder I, with the A. C. circuit, is thereby influenced, either directly or indirectly.

As can be seen from the diagram, the three 45 thermionic tubes R1, R2, and R3 are connected in parallel with the A. C. generator H, and at the grids of the said three tubes, D. C. potentials caused by the oscillations of each of the antenna systems are set up, which influence the 50 conducting powers of the tubes. The regulation of the working potentials most suitably is so chosen that in a case where no oscillations are transmitted, the tube represents an infinitely high resistance, whereas, upon the arrival of signal 55 waves, a biasing potential is set up at the grid

such that the A. C. circuit is closed as a consequence. If the internal resistance *w* of the receiver apparatus I is relatively high compared with the internal resistances of the tube used, the strength of the current flowing in the A. C. circuit will be nearly independent of whether all three tubes R1, R2, and R3 are simultaneously conducting or whether a positive grid potential is imparted from the incoming oscillations to say, only one of the tubes. Hence, this receiver 60 circuit acts like a limiting means which is passed by a current of unvarying intensity regardless of how many of the antenna systems are excited. The rectifier means may be so chosen that no 65 separate valves are provided, but that in the amplifier arrangement which amplifies the *rf* energy coming from the respective antenna system, the last tube is designed to act as a rectifying amplifier.

Hence, the arrangement hereinbefore disclosed 70 is suited for the recording of telegraphic signals and especially of pictures in black and white. By choosing a different adjustment of the value of the tube biasing potentials, also a quantitative 75 control of the A. C. in the pulsating-current circuit may be insured. It is, of course, important 80 that the connecting or transfer lines K, which are likely to be of considerable length, should be so designed as regards length and balance that no disturbing reflections or interferences of the 85 signals will be occasioned. For this reason, wherever necessary, recourse may be had to equalizing and phase-regulating means known 90 from cable engineering.

It is important in the sense of this invention 95 that the frequency of the A. C. generated by generator H should not be chosen unduly low, indeed, this frequency should be so chosen that the period of oscillation is small referred to the time-constants of the indicator or recorder apparatus. Under practical conditions, the frequency of the A. C. should probably be over 5000 cycles per second.

We claim:

1. The method of diversity reception which includes simultaneously making a plurality of energy collections of the same signal at the same wave length, but which have relatively different fading characteristics, separately rectifying each of the collected energies, utilizing each of the rectified energies to separately control the flow of locally generated alternating electrical energy, combining the resulting energies, and translating the combined energy.
2. The method of diversity reception which

5	includes collecting radiated energy of the same wave length at a plurality of geographically spaced points, separately amplifying each of the collected energies, separately rectifying each of the amplified energies, separately controlling the flow of locally generated alternating electrical energy in accordance with each of the rectified energies, combining the resulting energies, and translating the combined energy.	80
10	3. A diversity receiving system comprising a plurality of geographically separated antennas, each antenna being adapted to respond to the same wave length of the transmitted signal, a rectifier coupled to each of the antennas, a local source of alternating electrical energy, separate means to control the flow of the locally generated electrical energy in response to each of the rectified energies, means to combine the resulting energies, and means to translate the combined electrical energy.	85
15	4. A diversity receiving system comprising a plurality of geographically separated antennas, each adapted to respond to the same wave length of the transmitted signal, a detector coupled to each of the antennas, a plurality of electron emission tubes each having a control electrode so coupled to one of the rectifiers that the tube is made conductive upon reception of signal energy, a translating device, and a source of alternating electrical energy coupled to each of the tubes and to the translating device, so that the translating device is responsive to the combined energy controlled by all of the antennas.	90
20	5. A diversity receiving system comprising a	95
